COLLECTOR FUNNEL FOR USE IN TAKING FEMALE URINE SPECIMENS

Thomas N. Garland, 55 S. Washington St.,
Denver, Colo. 80209

Filed Nov. 7, 1966, Ser. No. 4,567

Term of patent 14 years

(Cl. D83—1)

FIG. 2

FIG. 1

FIG. 3

FIG. 4

FIG. 5

FIGURE 1 is perspective view of the collector funnel, for use in taking female urine specimens, illustrating my new design;

FIGURE 2 is a left side elevational view, the right side being a mirror image thereof;

FIGURE 3 is a rear elevational view thereof;

FIGURE 4 is a front elevational view thereof; and,

FIGURE 5 is a bottom plan view thereof.

I claim:

The ornamental design for a collector funnel for use in taking female urine specimens, as shown.
